LOCOMOTIVE

Paul A. Ketchpel, West Englewood, N. J., and Charles J. Surdykowski, Tuckahoe, N. Y.; said Surdykowski now by judicial change of name Charles J. Surdy; assignors to The Standard Stoker Company, Incorporated, a corporation of Delaware

Application April 8, 1932, Serial No. 603,928

8 Claims. (Cl. 198—15)

This invention relates generally to features of locomotive construction and more particularly to improvements in stoker equipped locomotives and has for its principal object the provision of an improved arrangement and organization with the locomotive of power actuating mechanism for locomotive accessories, particularly the stoker driving means.

It is also an object of this invention to provide means whereby the stoker driving motor or other power actuating means may be mounted rigidly to the underside of a locomotive deck and access thereto for purposes of inspection or repair may be conveniently had from above the deck.

It is a further object of this invention to provide such an arrangement whereby the stoker or other locomotive accessory driving motor may be mounted to occupy such space on the locomotive which has not heretofore been utilized.

With the above and other objects and advantages in view, the invention consists in the features of construction, the combination of elements and arrangement of parts hereinafter more fully described and claimed, and illustrated in the accompanying drawing, in which

Figure 1 is a central vertical longitudinal section through a portion of a locomotive with a stoker and stoker driving motor mounted thereon and shown in elevation, parts of which are broken away;

Figure 2 is an end elevation, partly in section and partly broken away, of the structure shown in Figure 1; and

Figure 3 is a sectional view taken on the line 3—3 of Figure 1.

In the drawing, the locomotive is represented generally by the numeral A, and comprises the engine unit 10 and the tender unit 10a, which are provided with a deck 11. The engine unit 10 includes a boiler firebox 12, at the rear of which is the usual water leg or backhead 13, the latter having a firing opening 14 therethrough.

The locomotive is provided with a suitable form of stoker, designated generally by the numeral 15, and which comprises a transfer conduit 16 leading from a suitable source of fuel supply, as from the tender 10a, forwardly beneath the locomotive cab deck 11 and above the frame 17. A riser conduit 18 extends upwardly and forwardly from the discharge end of the transfer conduit 16 through the deck 11 to the lower portion of the firing opening 14. The upper portion of the firing opening 14 may be closed by a suitable fire-door arrangement 19. The locomotive unit of the stoker 15 is supported from the locomotive

boiler backhead 13, preferably though not necessarily from the foundation ring 59 at its lower end by a bracket 51 and from the rear sheet of the backhead at its upper end through the flange 52 and suitable securing means.

Fuel may be conveniently delivered from the source of supply to the firing opening by a sectional screw conveyor comprising a screw section 20 in the transfer conduit 16 and a screw section 21 in the riser conduit 18. A distributor plate 22, extending into the firebox is arranged to receive the fuel delivered by the screw conveying system, and a pressure fluid blast issuing from the distributor head 23 projects the fuel into the firebox and over the firebed.

The locomotive and stoker construction thus far described while not in itself novel has been selected as the preferred form to which the present invention, which is now to be described in detail, is applicable.

The screw sections 20 and 21 are preferably driven from an engine 24 of the multi-cylinder reciprocating type, which in the instance shown, is rigidly mounted from the under side of the locomotive cab deck 11 on the left side portion of the locomotive and above the frame 17. The engine 24 comprises an engine bed 25 having side walls 26 and 27, end walls 28 and 29 and a floor 30. A cylinder block 31 is securely attached to an end wall of the engine bed. The usual valve mechanism (not shown) is employed for controlling the inlet and exhaust of steam to the cylinders 32. The cylinders 32 are provided with reciprocably mounted pistons (not shown) arranged to transmit power to a crank shaft 33, mounted in the bearings 34 in the side walls 26 and 27 of the engine bed 25.

The upper marginal edge of the engine bed 25 is provided with the horizontally and outwardly extending flange 35 bounding an opening 36 through which access may be had to the engine mechanism. Bolts 37 passing through the flange 35 and the cab deck 11 rigidly secure the engine bed 25 to the under side of the locomotive cab deck. The cab deck 11 is provided with a removable floor portion 38 overlying the opening 36 and rests at its marginal edge on the flange 35 forming a cover for the engine bed 25. Bolts 39 passing through the removable floor portion 38 and into the flange 35 bounding the opening 36 secure it in place, preventing coal dust from entering the engine bed. To insure a tight fit, a gasket 40 may be inserted between the floor portion 38 and the flange 35.

The base casting 41 of the riser conduit 18 has

a transverse bore 42 in which are mounted the worms 43 and 44 cooperating with suitable gearing and shafting for operating respectively the screw sections 20 and 21. The worms 43 and 44 are mounted on a transverse shaft 45. The adjacent ends of the separated shafts 45 and the crank shaft 33 are provided with the sprockets 46 and 47, respectively, over which passes a sprocket chain 48.

10 By securing the engine 24 to the underside of the cab deck 11 and mounting the engine cylinders from an end wall of the engine bed, access to the engine for purposes of inspection and repair is readily and conveniently made possible 15 by removing the floor portion 38 of the cab deck. At the same time, the engine is disposed so as to occupy only such space upon the locomotive which heretofore has not been used to any advantage.

20 The locomotive unit of the stoker 15 since it is supported from the locomotive boiler backhead, is free to move with the backhead as the latter expands and contracts. Likewise, since the stoker engine 24 is rigidly secured to the deck 11 which is attached to the boiler backhead, it also 25 is free to move with the backhead.

We claim:

1. In a locomotive provided with a cab, a deck for said cab, a locomotive accessory engine bed having an open top, a laterally extending flange bounding the marginal edge of said open top, means for rigidly securing said engine bed to the underside of said deck through said flange and a removable floor portion in said deck registering with the open top of said engine bed, said removable floor portion being supported from said engine bed and forming a cover therefor.

2. In a locomotive provided with a cab, a deck for said cab, a locomotive accessory engine bed rigidly secured to the underside of said deck, said engine bed having an open top, and a removable deck portion arranged to be supported from said engine bed and to form a cover therefor.

3. In a stoker equipped locomotive having a cab, a deck for said cab, a stoker prime mover rigidly secured to the underside of said deck and a removable floor portion in said deck and arranged to provide for access to said prime mover, said removable floor portion being supported from said prime mover and arranged to form a cover therefor.

4. In a locomotive provided with a cab, a deck for said cab having an opening therethrough, a locomotive accessory engine bed having an open

top registering with the opening in said deck, a flange extending laterally from the upper marginal edge of said engine bed, said engine bed being rigidly secured through said flange to the underside of said deck and a removable deck portion supported from said flange forming a closure for the opening in said deck and a cover for said engine bed.

5. In a locomotive provided with a cab, a deck for said cab having an opening therethrough, a locomotive accessory engine bed having an open top registering with the opening in said deck, a flange extending laterally from the upper marginal edge of said engine bed, said engine bed being rigidly secured through said flange to the underside of said deck, a removable deck portion forming a closure for the opening in said deck and a cover for said engine bed, said removable deck portion being supported on said flange, and means for securing said deck portion to said flange.

6. In a locomotive provided with a cab, a deck for said cab having an opening therethrough, a locomotive accessory engine bed having an open top registering with the opening in said deck, a flange extending laterally from the upper marginal edge of said engine bed, said engine bed being rigidly secured through said flange to the underside of said deck, said flange being arranged to form a seat with the marginal edge of the deck bounding the opening therethrough, and a removable deck portion forming a closure for the opening in said deck and a cover for said engine bed, said removable deck portion being received in said seat.

7. The combination including a substantially horizontal floor, a driving engine rigidly secured to the underside of said floor, said engine including a bed having an upwardly opened top, and a removable floor portion arranged to be supported from said engine bed and to form a cover therefor.

8. The combination including a substantially horizontal floor, a drive engine rigidly secured to the underside of said floor, said engine including a bed having an upwardly opened top, said floor also being provided with an opening registering with the opened top of said engine bed, and a cover plate insertable through the opening in said floor, said cover plate being secured to said engine bed and forming a cover for the opened top thereof.
